UNITED STATES PATENT OFFICE.

SPENCER OTIS, OF CHICAGO, ILLINOIS.

RAILWAY LOCOMOTIVE TERMINAL.

Application filed April 17, 1922. Serial No. 553,622.

To all whom it may concern:

Be it known that I, SPENCER OTIS, a citizen of the United States, residing at Chicago, in the county of Cook and State of Illinois, have invented certain new and useful Improvements in Railway Locomotive Terminals, of which the following is a specification.

This invention relates to a railway locomotive terminal, and has for its object to provide an improved construction and arrangement of locomotive houses in combination with a main track and branching tracks, whereby stalls of the locomotive houses may be rendered independently accessible from the main track, and which permits the performance of the necessary service to locomotives occupying said stalls and the return of the locomotives to service as soon as completed without obstructing the routing of one locomotive by another; also to provide a plant of this kind of large capacity with minimum occupancy of land area.

In locomotive roundhouses or houses constructed upon arcs of circles and dependent upon a turn table for delivery of locomotives to the respective stalls, much time is lost in getting a large number of locomotives into the different stalls over a single track of approach and single turn table. It has been proposed to substitute elongated or quadrilateral locomotive roundhouses, but these generally involve large land area for the field of trackage required to gain access thereto.

Now, the present invention provides for the use of elongated locomotive houses, but, by giving them special position, reduces to a minimum the land area required for trackage, brings them into a relation which greatly economizes in the use of fixed equipment for treatment of locomotives, and permits locomotive supplying and treating apparatus, as well as other adjunctive equipment, to be located in such spaces as are unavoidably defined by the particular locations selected for the houses and their trackage.

The underlying principle of the invention consists in positioning an elongated locomotive house, or preferably a pair of such houses, in the angle or angles defined between the main track and a perpendicular thereto, with the house diverging from both the main track and the perpendicular, so that stalls arranged across a house may have

independent tracks extended to and merged with the adjacent portion of the main track in a direction away from the perpendicular; the triangular space defined between the house or houses with their fields of trackage and the proximate portion of the main track being occupied by locomotive reversing means locomotive replenishing means such as a coaling and sanding station, boiler washing plant, a power house, etc., while the internal angular space between the houses is available through an extension of the reversing track for occupancy by a house or houses appurtenant or adjunctive to the locomotive houses; and the angular or divergent relation of the locomotive houses being particularly appropriate to the location of additional houses lying parallel thereto, and affording continuations of railroad stalls and accommodation for locomotive treating equipment in addition to that installed in the houses first named.

In order that the invention may be fully understood, the preferred and a modified embodiment thereof are illustrated in the accompanying drawings.

In said drawings—

Figure 1 is a schematic view of a locomotive terminal layout embodying the several features of the invention.

Figure 2 is a vertical longitudinal section through a series of parallel locomotive houses that enter into the plan of Figure 1; and

Figure 3 is a view similar to Figure 1 showing modifications in some of the details.

Figure 4 shows a modification.

1 represents a main track connected for the arrival and departure of locomotives from opposite directions. 2, 2, represent elongated or quadrilateral locomotive houses provided with a series of tracks 3 extending transversely thereof in series, and in such number as may be necessary to care for all the locomotives of a railroad division that it may be desired to accommodate at one time.

According to the present invention, houses 2 are located at a substantial angle to the main track 1 and also at a substantial angle to a perpendicular to said main track, which may be represented by the track 4, herein-after referred to; that is to say, each house 2, or but one thereof if but a single house be used, is placed to one side of the main track and to a perpendicular thereto, with

its longitudinal dimension diverging from both the main track and said perpendicular. Each stall 3 in a house 2 is connected by a spur track 5 with the main track 1, and these 5 spur tracks curve into merger with the main track 1 in a direction away from the perpendicular 4.

A number of advantages accrue from the adoption of an elongated or quadrilateral 10 locomotive house and its location in the particular relation to the main track and its perpendicular above described. The remote end of the house 2 represents the closest approach; it economizes in land area required for the plant; it permits the locomotive stalls to be arranged transversely of the house and therefore insures a maximum 15 number of stalls within the available longitudinal dimension of the house; and it leaves spaces for adjunctive or appurtenant 20 buildings, equipment, and apparatus with minimum increase of land area, the particular form of space left between the proximate end of the house and its trackage and 25 the portion of the main track adjacent the perpendicular 4, or between the main track and corresponding ends of both houses, being especially adapted to accommodate locomotive reversing means, such, for instance, 30 as the Y or triangular reversing trackage 6, the cinder disposal plant 7, boiler washing plant 8, power plant 9, and coaling and sanding station 10 with its tracks 11.

The perpendicular 4 will preferably be a track which constitutes an extension of the reversing Y, 6, and this may also have an extension 4^a which bisects the angle of the reversing Y to give access to cinder disposal pit 7. Located alongside of the track 4 or 35 its connected siding 4^b, may be a store house 12 with platform 13. This may enter between the interior angle formed by the two houses 2 with economizing of space. Pipes 13, 14 from the boiler washing plant 8 pass 40 longitudinally into the houses 2, being especially adapted by their location for such connection. The Y 6 is adapted to occupy the triangular spaces between the proximate 45 ends of the houses and the main track, being 50 made to substantially conform thereto. The base of this triangular reversing arrangement thus parallels the main track. In addition to the houses 2 others, such as the 55 house 15, having a bay 15^a containing small crane 16, and a bay 15^b containing large 60 cranes 17, 18, as well as the house 19 containing machine crane 20 and machine shop equipment 21, will preferably be located 65 along that side of one of the houses 2 which is remote from the main track 1, parallel to 70 said house 2 on the same side of the perpendicular 4 therewith, and having trackage 3^a in continuation of the trackage 3 so that the locomotive may be advanced to within 75 reach, successively, of the various apparatus

to be used in working upon it. Other buildings, such as the building 22 containing boiler machinery, buildings 23, 24, for storage, and building 25 for additional shop facilities, may be disposed in convenient relation to the buildings already named to facilitate the work to be performed.

According to Figure 3, the locomotive reversing means constitutes a turn table 6^a interposed in a siding 6^b, while an additional 75 siding 4^c is arranged to serve the cinder disposal pit 7. The coaling and sanding station 10 with its tracks 11 may also be located in triangular space between the houses 2 and the track 1, as already described.

From the foregoing description, it will be seen that the houses 2 in Figures 1 and 3 are located as sectors of a circle; that the main track lies outside of this circle parallel to a tangent thereto at a radius which divides the two houses; and that the branch tracks, curving from the main track toward the houses, enter the outer side walls of the houses with respect to the center of the circle. In other words, the arrangement of these figures simulates a portion of a round-house with the main track lying exterior thereto and the branch tracks entering the outer sides thereof.

According to Figure 4, a series of houses 2^a are distributed alongside the main track, in positions with their longitudinal dimensions lying at substantial angles to the main track and to perpendiculars thereto; with 100 proximate and remote ends of adjacent houses lying on opposite sides of perpendiculars to the track; with branch tracks curving from the main track toward and extended transversely of the several houses; 105 and with the nearest corners of the ends of the houses which are proximate to the main track located substantially on the line 26, 26^a which runs through points of curvature in the established curves of all the branch 110 tracks. The result of this arrangement is that the houses are completely surrounded by light; they are located as close to the main track as is practicable, thereby occupying as little lateral space as possible; and 115 the arrangement permits an indefinite extension of the locomotive house facilities.

Figure 4 involves the further feature of extending the tail of the reversing Y through a continuation of the curvature of one side 120 of the Y as shown at 4^c, so that it can be extended to any length without leaving the immediate vicinity of the terminal or getting off of the immediate right of way; and this disposition of the tail or extension of the 125 reversing Y permits the location of a storage house 12^a between it and the nearest locomotive house 2^a.

I claim:

1. In a railway locomotive terminal, the 130

- combination of a main track, an elongated locomotive house positioned adjacent and at an angle to the main track substantially less than a perpendicular thereto, and spur tracks diverging from the main track and entering said house through one side thereof.
2. In a railway locomotive terminal, the combination of a main track, an elongated locomotive house positioned adjacent the main track with its longitudinal dimension at substantial angles to the main track and to a perpendicular, a series of parallel locomotive stalls arranged across the locomotive house, and a field of spur tracks diverging from the main track and merging with said stalls.
3. In a railway locomotive terminal, the combination of a main track, an elongated locomotive house positioned adjacent the main track with its longitudinal dimension at substantial angles to the main track and to a perpendicular, a series of parallel locomotive stalls arranged across the engine house, and a field of spur tracks diverging from the main track and merging with said stalls; there being between the main track and the nearer portions of said house and field, means for reversing locomotives.
4. In a railway locomotive terminal, the combination of a main track, an elongated locomotive house positioned adjacent the main track with its longitudinal dimension at substantial angles to the main track and to a perpendicular, a series of parallel locomotive stalls arranged across the engine house, and a field of spur tracks diverging from the main track and merging with said stalls; there being between said main track and the nearer portions of said house and field, means for replenishing locomotive supplies.
5. In a railway locomotive terminal, the combination of a main track, an elongated locomotive house positioned adjacent the main track with its longitudinal dimension at substantial angles to the main track and to a perpendicular, a series of parallel locomotive stalls arranged across the engine house, and a field of spur tracks diverging from the main track and merging with said stalls; there being between said main track and the nearer portions of said house and field, means for replenishing locomotive supplies, and tracks extending from the main track through said replenishing means and back to the main track.
6. In a railway locomotive terminal, the combination of a main track, an elongated locomotive house positioned adjacent the main track with its longitudinal dimension at substantial angles to the main track and to a perpendicular, a series of parallel locomotive stalls arranged across the engine house, and a field of spur tracks diverging from the main track and merging with said stalls; there being between said main track and the nearer portions of said house and field, means for replenishing locomotive supplies, a triangular reversing track occupying said space, and locomotive treating apparatus located within the triangle of said reversing track.
7. In a railway locomotive terminal, the combination of a main track, an elongated locomotive house positioned adjacent the main track with its longitudinal dimension at substantial angles to the main track and to a perpendicular, a series of parallel locomotive stalls arranged across the engine house, and a field of spur tracks diverging from the main track and merging with said stalls; there being between said main track and the nearer portions of said house and field, means for replenishing locomotive supplies, and means for reversing locomotives.
8. In a railway locomotive terminal, the combination of a main track, an elongated locomotive house lying with its longitudinal dimension diverging from a portion of the main track and from a perpendicular thereto, a series of locomotive stalls extending across said house, a field of spur tracks extending from said stalls toward and curving into merger with the portion of the main track from which the house diverges and forming with the proximate portion of said main track a substantially triangular space, and a triangular reversing track occupying said space.
9. In a railway locomotive terminal, the combination of a main track, an elongated locomotive house lying with its longitudinal dimension diverging from a portion of the main track and from a perpendicular thereto, a series of locomotive stalls extending across said house, a field of spur tracks extending from said stalls toward and curving into merger with the portion of the main track from which the house diverges and forming with the proximate portion of said main track a substantially triangular space, a triangular reversing track occupying said space, and locomotive treating apparatus located within the triangle of said reversing track.
10. In a railway locomotive terminal, the combination of a main track, an elongated locomotive house lying with its longitudinal dimension diverging from a portion of the main track and from a perpendicular thereto, a series of locomotive stalls extending across said house, a field of spur tracks extending from said stalls toward and curving into merger with the portion of the main track from which the house diverges and forming with the proximate portion of said main track a substantially triangular space, a triangular reversing track occupying said space, and means for replenishing locomotive supplies related to the base of said triangle reversing track and adapted to supply locomotives standing thereon.
11. In a railway locomotive terminal, a

main track, an elongated locomotive house lying on one side of said main track in a position which diverges from the main track and from a perpendicular thereto, locomotive stalls extending across said house, spur tracks extending from said stalls and curved into merger with said main track in a direction away from said perpendicular, said house and spur tracks leaving between them and the proximate portion of said main track a triangular space, trackage branching from said main track into said triangular space, and an ash tunnel extending longitudinally of said house, beneath a plurality of stalls therein, and into delivery relation to the trackage in said triangular space.

12. In a railway locomotive terminal, a main track, an elongated house disposed to one side of said main track in position to diverge from the main track and from a perpendicular thereto, locomotive stalls extending across said house, spur tracks extending from said stalls to the main track and merging therewith in a direction away from said perpendicular, said house and spur tracks leaving between them and the proximate portion of the main track a triangular space, and a boiler washing plant located in said triangular space having pipes entering longitudinally into said locomotive house.

13. In a railway locomotive terminal, a main track, an elongated locomotive house located on one side of said main track and positioned to diverge from said main track and from a perpendicular thereto, locomotive stalls extending across said house, tracks extending from said stalls toward and merging with said main track in a direction away from said perpendicular, said house and spur tracks leaving between them and the proximate portion of said main track a triangular space, a triangular reversing track occupying said triangular space with its base substantially parallel to the main track, a track bisecting the apex of said triangular reversing track and extending into said triangular space, and an ash pit extending longitudinally of the house beneath a plurality of stalls therein and into service relation to said bisecting track.

14. In a railway locomotive terminal, a main track, an elongated locomotive house located on one side of said main track and positioned to diverge from said main track and from a perpendicular thereto, locomotive stalls extending across said house, tracks extending from said stalls toward and merging with said main track in a direction away from said perpendicular, said house and spur tracks leaving between them and the proximate portion of said main track a triangular space, a triangular reversing

track occupying said triangular space with its base substantially parallel to the main track, a track bisecting the apex of said triangular reversing track and extending into said triangular space, and a storage house located within said triangular space and in service relation to said bisecting track.

15. In a railway locomotive terminal, a main track, an elongated locomotive house lying on one side of said main track and positioned to diverge from the main track and from a perpendicular thereto at the proximate end of said house, locomotive stalls crossing said house, spur tracks extending from said stalls to and merging with said main track in a direction away from said perpendicular, and an additional locomotive house parallel to the house first named, contiguous to the side thereof remote from said main track, and lying on the same side of said perpendicular.

16. In a railway locomotive terminal, a main track, an elongated locomotive house lying on one side of said main track and positioned to diverge from the main track and from a perpendicular thereto at the proximate end of said house, locomotive stalls crossing said house, spur tracks extending from said stalls to and merging with said main track in a direction away from said perpendicular, and an additional locomotive house parallel to the house first named, contiguous to the side thereof remote from said main track, and lying on the same side of said perpendicular; said additional house having tracks arranged across the same in continuation of the stalls of said first-named house.

17. In a railway locomotive terminal, a main track, a plurality of elongated locomotive houses parallelly related to each other and positioned on one side of and at a substantial angle to said main track and to a perpendicular thereto, stalls extending transversely of said houses, and spur tracks extending from said stalls and merging with said main track in a direction away from said perpendicular.

18. In a railway locomotive terminal, a main track, a plurality of elongated locomotive houses parallelly related to each other and positioned on one side of and at a substantial angle to said main track and to a perpendicular thereto, stalls extending transversely of said houses, and spur tracks extending from said stalls and merging with said main track in a direction away from said perpendicular; said houses being, respectively, equipped for successive treatments of locomotives.

19. In a railway locomotive terminal, a main track, a plurality of elongated locomotive houses parallelly related to each other and positioned on one side of and at a substantial angle to said main track and to a

perpendicular thereto, stalls extending transversely of said houses, and spur tracks extending from said stalls and merging with said main track in a direction away from 5 said perpendicular; said houses being, respectively, equipped for successive treatments of locomotives, and the last house in the series constituting a machine shop lying beyond and having communication with the 10 respective stalls.

20. In a locomotive terminal, the combination of a main track, a pair of elongated locomotive houses lying on opposite sides of a perpendicular to said main track, in positions 15 diverging from said perpendicular and from the portions of the main track extending oppositely from said perpendicular, a series of locomotive stalls arranged across each house, and spur tracks extending from 20 the stalls of the respective houses toward the adjacent main track portions and then curving into merger with the latter in directions away from said perpendicular.

21. In a locomotive terminal, the combination of a main track, a pair of elongated locomotive houses lying on opposite sides of a perpendicular to said main track, in positions 25 diverging from said perpendicular and from the portions of the main track extending oppositely from said perpendicular, a series of 30 locomotive stalls arranged across each house, and spur tracks extending from the stalls of the respective houses toward the adjacent main track portions and then curving into 35 merger with the latter in directions away from said perpendicular; said houses and spur tracks leaving between their proximate ends and said main track a triangular space; and said triangular space being equipped 40 with locomotive reversing means.

22. In a locomotive terminal, the combination of a main track, a pair of elongated locomotive houses lying on opposite sides of a perpendicular to said main track, in positions 45 diverging from said perpendicular and from the portions of the main track extending oppositely from said perpendicular, a series of locomotive stalls arranged across each house, and spur tracks extending from 50 the stalls of the respective houses toward the adjacent main track portions and then curving into merger with the latter in directions away from said perpendicular; said houses and spur tracks leaving between their proximate 55 ends and said main track a triangular space; said triangular space being equipped with locomotive reversing means; said houses forming between their ends remote from said main track an interior angle; said 60 reversing track being extended into said interior angle; and an appurtenant house be-

ing located along said track extension in said interior angle.

23. In a railway locomotive terminal, a main track, an elongated locomotive house 65 located on one side of said main track and positioned to diverge from the main track and from a perpendicular thereto extending past the proximate end of said locomotive house, an appurtenant house located in the 70 angle between said locomotive house and said perpendicular, and trackage diverging from said main track past the proximate end of the locomotive house and into service relation with said appurtenant house. 75

24. In a locomotive terminal, a main track, locomotive houses symmetrically disposed with relation to said main track, a reversing Y between said houses and the main track, a locomotive supplying station located between the reversing Y and the main track, and branch tracks extending from the main track transversely into the houses; the trackage being arranged to permit locomotives in either house to proceed by forward 80 running past the supplying station.

25. In a locomotive terminal plant, elongated locomotive houses disposed as sectors of a circle, a main track disposed external of and parallel to a tangent of said circle and 90 a radius thereof lying between the houses, and branch tracks from said main track extending into sides of the respective houses remote from the center of the circle. 95

26. In a locomotive terminal plant, a main track, and a series of elongated locomotive houses distributed alongside the main track, each at a substantial angle to the main track and to a perpendicular thereto, with the proximate ends of the several houses adjacent the remote ends of antecedent houses 100 and on opposite sides of perpendiculars to the main track, and branch tracks curving from the main track toward and extending transversely of the houses. 105

27. In a locomotive terminal plant, a main track, and a series of elongated locomotive houses distributed alongside the main track, each at a substantial angle to the main track and to a perpendicular thereto, with the proximate ends of the several houses adjacent the remote ends of antecedent houses 110 and on opposite sides of perpendiculars to the main track, and branch tracks curving from the main track toward and extending transversely of the houses; the proximate ends of the houses coinciding substantially with the point of curvature and the established curve of said main tracks. 115

Signed at Chicago, Illinois, this 11th day 120 of April, 1922.

SPENCER OTIS.
